THOMAS M. LOTHROP, OF CHICAGO, ILLINOIS, ASSIGNOR TO ANGLE STEEL STOOL CO.,
OF OTSEGO, MICHIGAN, A CORPORATION.

DESIGN FOR A BENCH-LEG.

54,640.

Specification for Design.

Patented Mar. 9, 1920.

Application filed July 5, 1919. Serial No. 308,905. Term of patent 14 years.

To all whom it may concern:

Be it known that I, THOMAS M. LOTHROP, a citizen of the United States, residing at Chicago, in the county of Cook and State of Illinois, have invented a certain new, original, and ornamental Design for Bench-Legs, of which the following is a specification, reference being had to the accompanying drawing, forming part thereof.

In said drawing, Figure 1 is a perspective view of a bench leg, showing my design;

Fig. 2 is an end elevation of the same; and Fig. 3 is a top view of the same.

The top members of the bench leg are shown in full lines extending at one end only beyond the adjacent upright, but they may also extend beyond the other upright as indicated in dotted lines.

I claim:

The ornamental design for a bench leg, as shown.

THOMAS M. LOTHROP.
